UNITED STATES PATENT OFFICE

130,354

DESIGN FOR A HAND MIRROR OR SIMILAR ARTICLE

Everett W. King, Norwalk, Conn.

Application September 6, 1941, Serial No. 103,193

Term of patent 3½ years

To all whom it may concern:

Be it known that I, Everett W. King, a citizen of the United States, residing at Chestnut Hill Road, Norwalk, in the county of Fairfield and State of Connecticut, have invented a new, original, and ornamental Design for a Hand Mirror or Similar Article, of which the following is a specification, reference being had to the accompanying drawing, forming part thereof, wherein—

Figure 1 is a front elevational view of a hand

mirror or similar article showing my new design.

Figure 2 is a side elevational view thereof.

The back of the frame and handle is substantially the same as the front shown, and the back of the mirror portion is substantially plain.

I claim:

The ornamental design for a hand mirror or similar article, substantially as shown and described.

EVERETT W. KING.
